UNITED STATES PATENT OFFICE.

ELMER E. BILLOW, OF EVANSTON, ILLINOIS, ASSIGNOR OF ONE-HALF TO ADOLPHUS M. ALLEN, OF CHICAGO, ILLINOIS.

APPARATUS FOR DISTILLATION OF MINERAL OILS.

Application filed May 29, 1918. Serial No. 237,198.

To all whom it may concern:

Be it known that I, ELMER E. BILLOW, a citizen of the United States, and having residence at Evanston, in the county of Cook and the State of Illinois, have invented certain new and useful Improvements in Apparatus for Distillation of Mineral Oils, of which the following is a specification, reference being had to the accompanying drawings, forming a part thereof.

The purpose of this invention is to provide a method of distilling mineral oils which may be practised as a continuous process that shall be economical in operation and adapted to produce only a minimum deposit of free carbon from the oil which is treated. A further object of the invention is to provide suitable apparatus for the operation of such a process and the invention therefore consists in various operations and the means employed therefor, as hereinafter described and indicated by the claims. A specific form of suitable means is shown somewhat diagrammatically in the drawings which represent in vertical section a still in the form of a metallic chamber or tower associated with a so-called "lead kettle" and its furnace, together with other fittings and devices hereinafter described.

The method or process which is the subject of this invention will be described and explained in conjunction with a description of the apparatus illustrated in the drawing. The "lead kettle" referred to is a metallic bowl or vessel, whose wall indicated at 1, is of sufficient strength to support a molten mass of lead, 2, carried in the bowl, and is provided with a flange, 3, by which the vessel is carried on the walls of its furnace which is shown in the drawings as of the oil-burning type, provided with an oil supply valve, 4, controlling a nozzle, 5, associated with a mixing chamber, 6, adjacent a combustion chamber, 7, in which a flame-deflecting arch, 8, with a curtain, 9, serves to properly distribute the flame and heat of combustion over the under surface of the lead kettle, 1, so as to keep the molten lead, 2, therein, at a temperature substantially uniform throughout its mass.

Surmounting the molten bath, 2, there is shown a chamber constituting the still which is in the form of a metallic tower, 10, having at its lower end a depending flange, 11, which dips into the molten bath sufficiently

deep to hermetically seal the chamber, 10, there-over. A laterally-extending flange or suitable lugs at 12, resting upon the upper edge of the lead kettle, 1, provide support for the tower or chamber, 10, and its walls 60 are preferably insulated with a suitable covering, 13, to retain the heat as completely as possible within the chamber, 10. At its upper end the chamber is provided with a discharge opening and a conduit, 14, leading 65 therefrom to a suitable condensing apparatus and other refining devices, not shown.

For introducing the oil into the chamber, 10, there are provided supply pipes, 15, terminating preferably in a spray nozzle, 70 adapted to atomize the oil and to discharge it under sufficient pressure so that as it enters the chamber, 10, which is not under any appreciable pressure, it will at once assume a very finely divided condition 75 descending through the chamber in the form of a cloud or mist. The drawing illustrates two sets of spray nozzles at 16 and 17 respectively, and while the representation is only conventional, it will be understood that the nozzles, 16, are mechanical atomizers only, while the nozzles, 17, are an alternative type, adapted to employ a supply of compressed air or other expansible gas or vapor, 80 for accomplishing the atomization of the oil supplied from pipes, 15. A supply pipe, 18, for such auxiliary gas or vapor is shown in the drawing. It will be understood, however, that any gas or vapor furnished through the pipe, 18, for the purpose of 85 atomizing the oil must be of such a nature or quantity as not to form an explosive mixture with the oil in the chamber, 10. By hermetically sealing the chamber, 10, by immersion of its flange, 11, in the molten mass, 2, it is the intention to operate the process at approximately atmospheric pressure substantially in the absence of air, thus rendering it perfectly safe from explosion. On the other hand, it will be found that certain gases or vapors can be introduced through the pipe, 18, which will materially assist in the distillation process, or which will chemically combine with some products 90 of the process with beneficial results.

Since the spray nozzles, whether of the mechanical pressure-operated type, 16, or of the blast-operated mixing type, 17, comprise interiorly certain relatively small apertures through which the oil is fed, 110

which apertures may frequently become clogged or fouled by solid impurities in the oil, it is desirable that the nozzles be arranged for cleaning of these small interior openings without interruption of the distillation process. This may be accomplished by providing each of the oil-supply openings, 19, in the wall of the chamber, 10, with a corresponding plurality of nozzles which may be rotatably mounted for successive individual registration with such opening, 19, as indicated in the drawing. This shows a central fitting, 20, carried on a base plate, 21, in which two or more similar nozzles are concentrically mounted with respect to an axis of rotation of the plate. Each nozzle may be provided with an individual control valve, 22, and all the valves may be kept closed except the valves of nozzles actually in registration with the openings, 19. When a given nozzle requires cleaning its valve need merely be closed and the plate, 21, rotated a part of a turn to bring the next nozzle into registration with the opening, 19, and upon opening the valve of the newly positioned nozzle, the discharge of oil will at once be resumed through the particular opening. While the drawing shows only two openings, 19, it may be understood that any desired number may be provided so that the momentary shutting down of a single nozzle will not materially affect the total supply of oil to the still and will by no means interrupt the continuity of the distillation process. Where nozzles of the type, 17, are employed, the central fitting, 20, may be supplemented with an additional fitting, 23, and corresponding branch pipe, 24, for individually supplying the nozzles, 17, with the gas or vapor furnished through pipe, 18, but where the mechanical pressure type of atomizer, 16, is employed, a single oil supply pipe, 15, leading to the fitting, 20, is merely connected by a series of branch pipes, 25, with the individual nozzles, 16.

With certain grades of oil it will be preferable to pre-heat the oil before supplying it to the atomizing nozzles, and for this purpose any suitable heat supply may be utilized. The drawing shows the main oil supply pipe, 26, leading to a coil, 27, located within the molten heat-transmitting bath, 2, the terminal of the coil being shown at 28 as a branch fitting connected to the supply pipes, 15. It will be noticed that the pipe, 26, and also the terminal of the coil, 27, respectively enter and emerge from the molten bath, 2, laterally outside the depending sealing flange, 11, passing through the supporting flange or lug, 12, but in no way interfering with the seal of the tower or chamber, 10.

If the nozzles, 16 or 17, by which the oil is introduced into the still are fairly high

up in the chamber, 10, and thus at a considerable distance from the surface of the bath of lead or other molten material at 2, the distillation of many grades of oil injected at this position in the tower, 10, will proceed by stages as the finely divided vapor falls through the chamber toward the hot molten mass. The cloud or mist of oil descending in the chamber, 10, under the influence of gravity will be broken up into the various products by volatilization due to the heat in the chamber. The degree of heat in the vicinity of the injecting nozzle, 16 or 17, will be sufficient to almost immediately volatilize the lighter oil products as they enter the tower in this finely divided condition, and by virtue of their rapid expansion in volume, they will at once pass out through the conduit, 14, to the condensers and other apparatus above mentioned but not shown. The heavier oils descending into the more intense zones of heat will also, for the most part, be volatilized before actually reaching the surface of the molten bath, 2, so that with certain grades of oil there will be nothing left to form a carbon deposit on the bath, and in some cases, even though a portion of the oil vapor may actually come in contact with the molten bath, it will not necessarily throw down any solid carbon.

However, it is contemplated that certain other grades of oil will necessarily produce more or less of a carbon deposit, but owing to the molten condition of this heating element, there will be no difficulty in collecting and removing such carbon, whether it is deposited in loose graphitic form or crystallized in a hard crust. In either case the presence of carbon on the surface of the bath would materially reduce its heat-radiating efficiency, and it is therefore desirable that such carbon deposit be quickly removed. If the apparatus be so designed that the cross-section area of the tower, 10, is somewhat less than the exposed area of the molten bath, 2, the portion of the lead kettle, 1, which is not immediately surmounted by the tower, 10, may serve the purpose of a clean-out well for the removal of such carbon deposits. Except during the operation of cleaning, the surface of the lead or other material will preferably be protected from the air by a hinged cover, 29, but upon raising this cover, a tool such as that shown at 30, may be inserted in the bath and manipulated to reach up under the immersed flange, 11, and up to the surface of the bath within the chamber, 10. The tool, 30, which is illustrated is in the nature of a clam shell or two part receptacle carried on a bent tubular handle, 31, through which the operating connections for opening and closing it extend to an operating lever, 32. With such a device or any other suitable apparatus, it will be

possible to reach in and engage the carbon deposited on the surface of the molten bath in the chamber, 10, and withdraw such carbon through the molten mass and out by way of the clean-out wall without introducing air into the still, or without the necessity of packed connection through which air might leak into it. It is thus seen that the removal of carbon in no way interrupts the continuity of the distillation process, and can be effected at any time during the process so that for all practical purposes, the surface of the molten bath, 2, may be kept clear of carbon, even in the event of a relatively heavy deposit. With most grades of oil however, in view of the fact that the process is carried on in the absence of air, and preferably in a tower, 10, of considerable height, the very great majority of the oil will be entirely volatilized without deposit of carbon.

I claim:—

1. An apparatus for distilling mineral oil comprising an upwardly open receptacle containing a quantity of lead and means for heating said lead sufficiently to render it molten, a tower surmounting the lead container and sealed thereover to exclude air, openings in the tower at the upper part thereof, a plurality of oil injecting nozzles movably mounted adjacent each opening, arranged to be selectively registered therewith, and means for closing the opening to exclude air from the apparatus during the interchange of nozzles, said movably mounted nozzles constituting means whereby the feeding of oil through the said openings will be practically uninterrupted.

2. An apparatus for distilling mineral oil comprising an upwardly open receptacle containing a quantity of molten lead, a source of heat for maintaining said lead at high temperature, a tower surmounting the lead sealed there-over to exclude air, a spray nozzle for atomizing and injecting oil posi-

tioned in the wall of the tower at a substantial distance above the lead and a discharge conduit leading from the upper portion of the tower.

3. An apparatus for distilling mineral oil comprising an open bowl containing a quantity of molten material, a source of heat arranged to maintain the temperature of the molten material, a vertically disposed chamber or tower over said molten material having the lower edges of its surrounding walls immersed therein, thus hermetically sealing the tower by such immersion and causing the heat of the molten material to be confined and rise within the said tower without materially increasing the pressure therein above atmospheric pressure; means for injecting oil into the tower at the upper portion thereof, whereby the oil thus injected will be subjected to the action of the heat confined and rising within the tower and a conduit at the top of the said tower leading therefrom for the discharge of the volatilized products.

4. In an apparatus for distilling mineral oil comprising a bath of molten material, a downwardly open chamber covering a portion of the surface of said bath and hermetically sealed thereto by immersion of its side walls therein, means for removing foreign matter from the surface of the bath within said chamber comprising a tool adapted for insertion in a portion of the bath not covered by the chamber and formed to reach under the submerged edge of the side wall of said chamber and up to the surface of the bath therein, for engaging a quantity of said foreign matter and withdrawing it through the molten mass.

In testimony whereof, I have hereunto set my hand at Chicago, Illinois, this 18th day of May, 1918.

ELMER E. BILLOW.
